UNITED STATES PATENT OFFICE.

HARRY A. TRUESDALE, OF CONNEAUT, OHIO, ASSIGNOR TO CONNEAUT CAN COMPANY, OF CONNEAUT, OHIO, A CORPORATION OF OHIO.

SEAL AND TUBULAR INLET FOR CANS AND OTHER RECEPTACLES.

No. 807,223.

Specification of Letters Patent.

Patented Dec. 12, 1905.

Application filed September 2, 1903. Serial No. 171,707.

To all whom it may concern:

Be it known that I, HARRY A. TRUESDALE, a citizen of the United States, residing at Conneaut, in the county of Ashtabula and State of Ohio, have invented certain new and useful Improvements in Seals and Tubular Inlets for Cans and other Receptacles; and I do hereby declare the following to be a full, clear, and exact description of the invention, such as will enable others skilled in the art to which it appertains to make and use the same.

This invention relates to metallic seals for the tubular screw-necks or inlets of cans; and it consists in the construction and combination of parts hereinafter more particularly set forth and claimed.

In the accompanying drawings, Figure 1 represents a side view of a screw-neck for a can and a seal embodying my invention with a tool in the act of applying the seal to said neck, the last-named part being in central vertical section, the other parts in side elevation. Figs. 2, 3, and 4 represent, respectively, detail perspective views of the screw-neck, the seal, and the cover, a small part of the top of the can being shown with the first-named in Fig. 2 and a part of the peripheral wall of the seal being broken away in Fig. 3.

30 A designates the tubular screw-neck, having an upwardly and inwardly tapered annular bearing A' in its upper part to receive the correspondingly-formed tapering circular periphery of the body B' of the cap or seal B, which closes the said screw-neck. The said seal has a central inner recess B², corresponding to the said body B' and caused by striking up the latter. The exterior of the said screw-neck has a circular bead or "hollow wire" a formed thereon, and the upper part of the said seal or cap has an annular flange b overlapping the said bead or wire and adapted to be pinched in or bent or curved under the same to lock the said seal or cap securely to the said screw-neck. This pinching, curving, or bending is most conveniently effected by means of a pair of pliers C, forming the subject of my application, Serial No. 168,097, filed August 3, 1903, the construction of which need not be 45 more particularly described here.

A³ designates an external screw-threaded cap which constitutes no part of the present invention, being old and common, but may be screwed on the neck A as a supplementary

protective cover while the seal or cap B is in place or as a temporary alternative closure when said cap or seal is absent.

The above-described construction of seal and screw-neck insures a very secure lock between the parts, while attaining all the advantages of a tapered joint, which will of course tighten as the seal is pressed into its seat in the neck. The seal is of one piece of metal or equivalent substance having the necessary degree of flexibility and stiffness. It must of course be sufficiently stiff to permanently retain its shape against gaseous pressure or any normal accidental pressure, yet sufficiently flexible to yield to a tool applied at its edge by normal force, as described. Of course the seal may be applied in this way to any tubular part provided with the necessary bead or outwardly-turned rim and bearing and adapted to fit the said seal. The screws of the screw-neck have no function in combination with the said seal and may be dispensed with, but are here retained in description and illustration because of their common use as outlets and inlets for cans and similar receptacles. Since the lock between the parts is altogether external, there is no risk of scratching either of the bearing-surfaces by projections. Furthermore, the external locking parts are easily accessible for unlocking at will.

When the annular flange or downwardly-extending outer part b of the cap is pinched in, as before stated, by the tool above mentioned, whether at one point or more than one point of its periphery, it will necessarily at such point or points of pinching be curved or bent against the neck of the can and under the bead of the said neck, closely engaging the same and locking the cap thereto. In practice this pinching or crimping is usually effected at several points, although one such impression will often suffice as a lock, or, if preferred, the tool may be shifted but very slightly from point to point, making the impressions practically continuous, though said tool is not adapted nor intended to roll a continuous edge under the bead of the neck. Neither soldering nor cement is needed to lock the cap and the can-neck, which two parts constitute the closure of the can; but a little cement is placed as a filling or packing only in the annular groove of the cap formed by the bend of the upwardly and downwardly

extending portion ending in the flange thus impressed. This cement is solidified before the cap is applied and fits on the bead or rim of the neck, coöperating with the fit of the 5 tapered body of the cap against the inner face of the neck and with the fit of the flange of the cap against the bead or rim to make a perfect fluid-tight seal when put in its place by hand before any tool has been applied or 10 any impression made. The cap is, indeed, complete as a seal without any impression or bending of its flange or downwardly-extending outer part and is often thus used, the only objection being the risk of dislodgment, 15 as it holds its place by friction only. The application of the tool by pinching in the flange under the bead at intervals provides the desired means of positive locking.

Having thus described my invention, what 20 I claim as new, and desire to secure by Letters Patent, is—

1. A can-top having a neck of less diameter than the said top and provided with an upwardly-extending flange, the upper portion 25 of which is curved over to form a bead with the free edge against the said flange, in combination with a cap having an upwardly-ex-

tending portion engaging the inner side of said flange and a downwardly-extending portion surrounding the said bead, the edge of 30 said downwardly-extending portion being curved inwardly against the flange and closely engaging said bead, whereby said cap is securely joined without soldering.

2. A can-top having a closure including a 35 raised flange the upper portion of which is curved over to form a bead with the free edge against the said flange, in combination with a cap having an upwardly-extending portion 40 engaging the inner side of the said flange and a downwardly-extending portion surrounding the said bead, the edge of said downwardly-extending portion being bent inwardly against the flange and closely engaging said bead whereby said cap is securely 45 joined without soldering.

In testimony whereof I have signed my name to this specification in the presence of two subscribing witnesses.

HARRY A. TRUESDALE.
